UNITED STATES PATENT OFFICE.

WALTER P. GRATH, OF ST. LOUIS, MISSOURI.

BRICK-MACHINE.

1,192,057.

Specification of Letters Patent. Patented July 25, 1916.

Application filed August 10, 1914. Serial No. 856,107.

To all whom it may concern:

Be it known that I, WALTER P. GRATH, a citizen of the United States, and a resident of the city of St. Louis and State of Missouri, have invented a new and useful Improvement in Brick-Machines, of which the following is a specification.

This invention relates to machines of the type shown in my Patent No. 791,262, dated 10 May 30, 1905, for pressing bricks from comparatively dry clay, but it is not restricted to pressing dry clay bricks.

The object of this invention is to provide for the rapid escape during the pressing 15 operation of the air that permeates clay powder and loose clay, and thereby to enable the speed of operation of the machine to be increased.

A further object of the invention is an arrangement of parts whereby the plungers and molds can be readily changed, and the moving parts can be removed and replaced without dismantling the entire machine.

Other objects of the invention are to reduce vibration of the machine and its moving parts, to equalize the stresses on the various parts, and to reduce the number of parts and the overall dimensions of the machine.

30 The invention consists in a machine for accomplishing the foregoing and similar objects.

The invention further consists in the parts and arrangements of parts of the machine 35 which constitutes the preferred form of the invention, as shown in the accompanying drawings and hereinafter described and claimed.

In the drawings, in which like characters 40 designate like parts in the several views, Figure 1 is a side elevation of a brick machine constituting the preferred form of the invention; Fig. 2 is a front elevation of the same, one side frame and parts associated 45 therewith being shown in cross-section; Fig. 3 is a rear elevation of the same, part of the bed being broken away and one side frame and parts adjacent thereto being shown in cross-section on the center line of the main 50 shaft; Fig. 4 is a longitudinal vertical section of the same taken alongside of the middle plane of the machine; and Figs. 5 to 9, inclusive, are partial views of the working parts of the machine showing the relative

positions of the plungers at successive stages 55 in the operation of pressing a brick.

Referring to Figs. 1 to 4 inclusive, the frame of the machine consists of a bed plate or base 11, and side frame members 12 bolted to the base and connected at their upper 60 front edges by a cross-brace 13. Each of the side frames consists of a horizontal bottom portion, a vertical pillar at the front, and a downwardly sloping back brace from the top of the pillar to the bottom portion. 65

The upper and lower end portions of the vertical pillars have vertical slots 14 therein, and the outer faces of said pillars are ribbed or channeled to increase their rigidity and strength and to serve as guideways for 70 the side links 15 hereinafter mentioned.

Through the slots in the upper ends of the pillars extend the ends of a shaft 16, which ends are flattened on the sides to fit and slide in said slots. Journaled on this shaft 16 is 75 the upper link 17 of a toggle-joint 18 whose lower link 19 is pivotally connected to a cross head 20. The ends of the cross head are arranged to fit and slide between vertical guides 21 provided therefor, which are bolted on to the inner faces of the vertical pillars. This cross head carries a number of plungers 22, each of which is arranged to co-operate with a mold 23 provided therefor in a cross member or mold block 24 which is 80 supported at its ends on the side frame. The mold block 24 slides in horizontal grooves 25 on the inside faces of the side frames, and may be removed and replaced 85 as desired. 90

In the machine shown in the drawings, there are four top plungers 22 and four molds 23, arranged side by side in a single row. The molds have slightly tapering sides, the length and width of the molds being about an eighth of an inch greater at the top than at the bottom. The molds have a considerably greater depth than the thickness of the bricks which they are designed for making, so the difference in size between 100 the top and bottom faces of the bricks is inconsiderable. The molds are made to conform near the bottom to the desired size of the bricks, and at the tops they are slightly larger than the bricks. This shape enables 105 the bricks to be readily ejected from the molds without injury.

A bar 26 is pivotally connected to the tog-

gle joint 18 for actuating the toggles. This toggle actuating bar 26 is operatively connected at its other end to cam actuating mechanism. In the preferred construction, as illustrated in Figs. 3 and 4, the end of the toggle actuating bar is bifurcated or slotted to fit over the main shaft 27, and a cap 28 is bolted over the end of the slot. Cam rollers 29 are mounted on opposite sides of the bar at a point near its slotted end, and between the shaft and the pivot of the toggle. These rollers run in cam grooves in the opposing faces of two cams 30 that are fixed to said shaft 27 on opposite sides of the bar 26. The grooves of said cams are of an irregular shape resembling a heart, and are similar to and the reverse of each other. For about one quarter of a circumference each groove is a circular arc of greater radius than at any other portion of the cam; and consequently when the rollers are in this portion of the groove, the bar maintains the toggles bent, and the plungers 22 are held in their uppermost position. A notch 31 is cut in the outer wall of this portion through which the rollers may be inserted and removed whenever the toggle actuating bar is taken off of the cam shaft. At the end of this circular portion, the cam groove has a short concave portion or cusp which first approaches half way to the center and then recedes from the center to a radial distance less than the radius of the circular arc. The remaining portion of the groove subtends an angle somewhat greater than 180 degrees, and is in the form of a flat convex curve passing around and close to the center of the cam. By this arrangement, the middle of the flat convex curve portion of the groove is very close to the shaft, and when the rollers engage in this region a considerable angular travel of the cam produces a very slight longitudinal movement of the toggle actuating bar. The parts are so proportioned that the cam rollers are closest to the cam shaft at the time when the toggle levers are in alinement with each other, which is the position of maximum pressure on the brick. By this arrangement, a most powerful compression is accomplished.

The bottoms of the several molds 23 are open, and bottom plungers 32 are slidably arranged for up and down movement therein. The bottom plungers are bolted on the upper face of a lower cross head 33, the ends of which project through and are slidably arranged in the slots 14, in the lower ends of the side frame pillars, and have rollers 34 on their extremities. The ends of the cross head just inside of the rollers are squared and fit in square holes in the lower ends of the side links 15, whereby the side links form slides for guiding the lower cross head.

65 The upper and lower portions of the outer

faces of the side pillars are finished to constitute guideways 36 for the side links 15. These guideways are provided with adjustably mounted wear plates 37, between which fit and slide the squared ends of the side 70 links. Suitable cover plates 38 are removably mounted on the outer faces of the upper ends of the pillars, and coöperate with said guideways to hold the side links. The upper ends of these links and of the cover 75 plates have overlapping vertical slots 39, 40 therein through which extend the flattened ends of the pivot shaft 16 of the upper toggle, said flattened ends being arranged to fit and slide in said slots. The slots 39 in the 80 side links terminate above the ends of the pivot shaft 16 with but little space between, but below the ends of the pivot shaft there is considerable space in the slots for relative sliding movement.

The ends of the pivot shaft rest in the lower ends of the slots 40 in the cover plates in charging position of the mechanism, and whenever the toggle-joint is bent to raise the upper plungers from the molds. In the 90 slot 39 at the upper end of each of the side links is a bearing block 41, which is secured in place by means of nuts screwed on a screw stud 42 that is attached to the bearing block and extends through the top end of 95 the link. These bearing blocks constitute upper limit stops for the ends of the pivot shaft 16 of the upper toggle. In the operation of the device, as the toggle links are straightened out by the movement of the 100 actuating bar, the lower links move downwardly with the upper cross heads and plungers until further movement thereof is resisted by the clay. Further straightening of the toggle-joint causes the upper toggle 105 link to move upwardly until its pivot shaft 16 bears against the upper bearing or limiting blocks 41, whereupon the further straightening of the toggle-joint simultaneously forces the lower cross head upwardly 110 and the upper cross head downwardly with substantially equal force. The bearing blocks 41 can be removed and replaced with others of different thickness in order to adjust the spaces between the plungers to conform to the thickness of the bricks. By this arrangement, the cross heads are jointly actuated by the actuating bar and toggle-joint, and are relatively adjustable without affecting their normal vertical positions. 120 The actuating bar can lift the upper cross head without affecting the lower cross head, and the side links can move upwardly and downwardly with said lower cross head independently of the upper cross head, for 125 the purpose hereinafter described.

The lower cross head 33 rests at the middle on a lever 43 which is mounted on a horizontal cross shaft 44 provided therefor and supported in the side frames. The 130

front end of said lever is adjustably supported and cushioned on springs 45 provided for the purpose. The adjustment of the lever 43 is by means of a vertically arranged screw 46 which is swiveled or stepped at its upper and lower ends in bearings 47 provided therefor on the front of the frame. A hand wheel 48 is secured to the screw for turning the same. A movable nut or block 49, which is held flatwise against the front of the frame to prevent rotation, works up and down on the screw 46 and constitutes a vertically adjustable abutment for the springs 45 that support the end of the lever 43. By manipulating the screw, the lower cross head is positioned to support the bottom plungers 32 in the lower ends of the molds at the height corresponding to the desired capacity of the molds. The lower cross head rests on the adjusting lever only just before and during the operation of charging; hence this adjustment of the cross head support does not affect the position of the cross head and plungers during the several stages of compression.

The lower cross head is raised independently of the upper cross head by means of side levers 50 pivotally mounted on the ends 30 of the cross shaft 44 outside of the side frame. The front ends of the side levers 50 have slots 51 within which engage the rollers 34 on the ends of the lower cross head. The rollers and side levers are held 35 in assembled position by means of washers 52 arranged on the ends of the crosshead and secured by wedge-shaped pins 53. The rear ends of the side levers 50 are positioned below the extremities of the main 40 shaft 27, and carry rollers 54 on their upper sides. The rollers are journaled in bearings on standards 55 which are removably mounted on the ends of the side levers by means of a bolt 56 secured to the under side of each 45 standard and passing through a vertical hole in the end of the lever. Cams 57 are secured to the ends of the main shaft in position for their peripheries to engage the rollers 54 which are adapted to roll 50 thereon. Each cam has two projections which are shaped to depress the cam roller and thereby tilt the side lever twice during each revolution of the main shaft. The first projection 58 is a comparatively short one, and tilts the side lever through an angle such that the plungers on the lower cross 55 head are raised about half way to the top of the molds and then lowered, with but a brief interval during which the cross head 60 remains in raised position. The second projection 59, which is spaced about a quarter turn behind the first, raises the lower cross head sufficiently to carry the bottom plungers to the tops of the molds, thereby 65 ejecting the bricks therefrom, and holds the

cross head in raised position during a sufficient interval for the charging mechanism to discharge the bricks on the front table 60.

The cams 57 for raising the lower cross head are timed with respect to the cams 30 70 for actuating the toggle links in order to raise the lower cross head to eject the bricks concurrently with the withdrawal of the upper plungers from the molds. The lifting of the lower cross head half way to the 75 tops of the molds occurs simultaneously with the short reverse or upward movement of the upper cross head during its downward pressing stroke.

The charging mechanism may be of any 80 ordinary type. In the construction illustrated, it comprises a front table 60 and a rear table 61 bolted to the side frames flush with the top of the cross member containing the molds at the front and rear thereof, respectively, and a hopper 62 above the table on the rear side of the front pillars of the frame. A hollow slide 63, which is adapted to receive and deliver a sufficient amount of clay to fill the molds, is moved back and forth 85 at intervals by means of bars 64 which are slidably mounted in ways 65 in the side frames. Cams 66 mounted on the shaft 27 are arranged to move the slide forwardly when the bottom plungers are raised flush with 90 the upper surface of the mold block and table, and to return the slide after the plungers have been lowered to their normal positions. Each of the bars 64 has a pin 67 projecting through its rear end and the two 100 projecting ends of the pin are provided with rollers 68. One roller is arranged to engage the groove of the cam, and the other roller is arranged to engage the horizontal 105 way or groove 65 formed in the inner face of the adjacent side of the frame. The charging slide cam 66 has a notch 69 in its outer wall through which the cam roller can be withdrawn without dismounting the cam and shaft 27 upon which it is secured. 110

The main or cam shaft 27 may be actuated by any suitable mechanism. As illustrated in the accompanying drawing, the main shaft has a pair of large gears 70 fixed thereon, and these gears mesh with two pinions 115 71 mounted on an intermediate shaft 72 which is journaled at its ends in the side frame members. The intermediate shaft carries a larger gear 73 which in turn meshes with a pinion 74 on a pulley shaft 120 75. This pulley shaft is provided with a belt pulley 76 which constitutes a means for transmitting power from a suitable source.

In order to distribute stresses to the frame 125 advantageously, it is preferable to arrange all of the gears, pinions, cams, and levers symmetrically with respect to the side frame members. In the construction illustrated, all of the working parts with the exception of 130

the side links and levers and the cams for operating them are inside of the framework, thereby securing great compactness and minimizing the destructive tendencies of unbalanced pressures.

The operation of the machine is as follows: Starting with the parts in charging position, as shown in Figs. 1, 2 and 5, the charging slide 63 having moved forward with sufficient powdered clay to fill the molds, rotation of the main shaft in the direction of the arrow will retract the charging slide and partly straighten out the toggle-joint. The cams for operating the side levers are out of contact with the cam rollers during the charging operation and first part of the compressing operation. At this stage of the operation the plungers and charging slide occupy positions approximately as shown in Fig. 6, the bricks being partly compressed and positioned near the bottoms of the molds. Further rotation of the main shaft causes the cusp portions of the cams 30 which actuate the toggle actuating bar to engage the rollers on the toggle actuating bar to reverse the movement of the bar and lift the upper cross head. At the same time, the projections 58 of the side lever cams depress the side levers and raise the lower cross head. The lower cross head and the upper cross head are maintained at approximately the same distance apart during their upward movement, thereby raising the bricks to the outwardly flaring tops of the molds, as shown in Figs. 4 and 7, and allowing any air confined therein to escape readily from their sides. The upper cross head moves slightly farther than the lower, whereby the pressure on the bricks is released and the confined air can escape from the top and bottom faces also. Further rotation of the main shaft carries the projections 58 of the side cams past the rollers and allows the lower cross head and plungers to drop. Simultaneously therewith the toggle actuating cams straighten out the toggle-joint and compress the bricks to the desired thickness, the side links causing the working pressure to be applied with substantially equal force to both the top and bottom cross heads and plungers, as shown in Fig. 8. Further rotation of the main shaft bends the toggles and raises the top cross head and plungers, and simultaneously therewith the projections 59 of the side cams depress the side levers and raise the lower cross head and plungers to eject the bricks, as shown in Fig. 9. The circular or dwell portions of the toggle actuating cams and side cams hold the plungers in the positions shown in Fig. 9 while the charging mechanism discharges the bricks and refills the molds with clay.

From the foregoing it appears that in carrying out this invention, the operation

of pressing the brick is effected in two stages. The first or initial stage consists in compacting the clay in the molds and then retracting or raising the plungers high enough to permit the compressed air to escape from the molds. The second stage consists in submitting the compacted clay to the full force of the press. By reason of the compressed air being permitted to escape after the initial compacting of the clay, the full force of the press becomes effective in compressing the brick; whereas if the entire compressive force had been exerted in one movement, the entrapped air would have exerted considerable resistance, and some of the air would have been trapped in the interstices of the clay and compressed. Unless air compressed in the interstices of the bricks is allowed time to escape before the pressure on the bricks is removed, there is considerable likelihood that the mass of clay will be disrupted by the pressure within upon the removal of the outside pressure. Such a result is entirely obviated by this invention, which enables the speed of operation of the machine to be increased as far as safety will permit without the bricks bursting open when they are discharged from the molds.

Obviously, the means hereinbefore described for permitting the escape of the air prior to the final compression of the clay admits of considerable modification, and I do not wish to be restricted to said construction.

I claim the following as my invention:

1. A brick machine having a mold with open top and bottom, the top portion of the side walls of said mold being formed to permit the escape of air, upper and lower movable plungers forming the top and bottom of said mold, means for causing said plungers to approach each other to form a brick, and means for retracting the upper plunger before the completion of the working stroke and concurrently raising the lower plunger to a point short of the top of the mold, whereby the partly formed brick is raised to the top of the mold to allow the escape of imprisoned air.

2. A brick machine having a mold with open top and bottom, and tapering walls slightly narrower at the bottom than at the top, upper and lower movable plungers forming the top and bottom of said mold, means for causing said plungers to approach each other to form a brick, and means for retracting the upper plunger before the completion of the working stroke and concurrently raising the lower plunger to a point short of the top of the mold, whereby the partly formed brick is raised to the top of the mold to allow the escape of imprisoned air.

3. In combination in a brick machine, a

5 mold having open ends, one of which is larger than the other, oppositely facing plungers adapted to enter the ends of the mold to compress a brick between them, means for moving said plungers toward each other simultaneously, and means for relatively moving said plungers jointly with respect to said mold during the compressing operation, whereby the brick is moved toward the larger end of the mold.

10 4. In combination in a brick machine, a mold having open ends, one of which is larger than the other, oppositely facing plungers adapted to enter the ends of the mold to compress a brick between them, means for moving said plungers toward each other simultaneously, and means for successively moving the brick first toward the larger end of the mold, and then toward the smaller end of the mold, during the compressing operation.

15 5. A brick machine comprising a frame, a mold supported in said frame, a toggle mounted in said frame, an upper plunger forming the top of said mold and connected to the lower end of said toggle, a lower plunger forming the bottom of said mold, links connecting the upper end of said toggle and said lower plunger, the upper 20 end of each of said links being slotted, a support for the upper end of said toggle independent of said links, an actuating shaft, and a pitman directly connecting said shaft and the middle pivot of said toggle, said frame having vertically alining upper 25 and lower guideways for the opposite ends of said links, and the lower plunger being fixed to the lower ends of the links and held in alinement thereby, said links and 30 lower plunger being independently movable with respect to said frame and upper plunger, and means for operating said lower plunger independently of said upper plunger.

35 6. A brick machine comprising a frame having slotted side pillars, a mold mounted in said frame, a toggle mounted in said frame, an upper plunger forming the top of said mold and connected to the lower 40 end of said toggle, a cross head having a lower plunger forming the bottom of said mold, slotted links outside of said frame connecting the upper end of said toggle and said cross head, said links being guided 45 in said pillars at their lower ends, means for raising said cross head, and means for independently actuating said toggle, said

cross head being adapted to be inserted through a slot in the pillar and having its ends secured to fit in squared holes provided 60 therefor in said links whereby it is rigidly held and guided thereby.

7. A brick machine comprising side frames having horizontal grooves on the inner sides thereof, a mold mounted on said frame adjacent to said horizontal grooves, a transverse power shaft journaled on said frame, grooved cams fixed on said power shaft adjacent to each of said horizontal grooves in the side frames, a horizontally 70 reciprocatable charger in coöperative relation to said mold, connecting bars operatively connected to said charger and interposed between said horizontal grooves in the side frames and said cams, and having oppositely disposed projections slidably fitted in the adjacent horizontal groove and cam groove, whereby said charger is intermittently reciprocated.

8. A brick machine comprising side 80 frames, a mold mounted on said side frames, a horizontally reciprocatable charger mounted on said side frames in coöperative relation to said mold, said side frames having oppositely disposed parallel horizontal 85 grooves on their inner sides, a transverse power shaft journaled on said side frames, continuously grooved cams mounted on said power shaft adjacent to the inner faces of said side frames, connecting bars secured at 90 one end to said charger and having oppositely disposed transverse rollers mounted on their opposite ends and fitting respectively in the adjacent horizontal groove in the side frame and the adjacent cam groove. 95

9. A brick machine having a mold with open top and bottom and tapering walls slightly narrower at the bottom than at the top, upper and lower movable plungers forming the top and bottom of said mold, 100 and means for operating said plungers.

10. A brick machine having a mold with open top and bottom and tapering walls, upper and lower movable plungers forming the top and bottom of said mold and movable up and down therein, and means for operating said plungers.

Signed at St. Louis, Mo., this 7th day of August, 1914.

WALTER P. GRATH.
